UNITED STATES PATENT OFFICE.

JESSE B. BRIDGEWATER, OF EMPIRE, COLORADO.

DESIGN FOR A RAIL-TIE.

53,353.

Specification for Design.

Patented May 27, 1919.

Application filed October 19, 1918. Serial No. 258,906. Term of patent 3½ years.

To all whom it may concern:

Be it known that I, JESSE B. BRIDGEWATER, a citizen of the United States, residing at Empire, in the county of Clear Creek and State of Colorado, have invented a new, original, and ornamental Design for a Rail-Tie, of which the following is a specification, reference being had to the accompanying drawings, forming part thereof.

The figure is a perspective view of a rail tie, showing my new design.

I claim:

The ornamental design for a rail tie, as shown,

JESSE B. BRIDGEWATER.
